UNITED STATES PATENT OFFICE.

CHARLES E. JOHNSON, OF DENVER, COLORADO, ASSIGNOR OF ONE-THIRD TO WILLIAM A. JOHNSON AND ONE-THIRD TO SIMON BITTERMAN, BOTH OF DENVER, COLORADO.

DESIGN FOR A CARBURETER BODY OR CASING.

57,659.

Specification for Design.

Patented Apr. 26, 1921.

Application filed May 12, 1919. Serial No. 296,702. Term of patent 14 years.

To all whom it may concern:

Be it known that I, CHARLES E. JOHNSON, a citizen of the United States of America, residing at the city and county of Denver and State of Colorado, have invented a new, original, and ornamental Design for a Carbureter Body or Casing, of which the following is a specification, reference being had to the accompanying drawing, forming a part thereof.

The figure is a perspective view of a carbureter or casing, showing my new design.

What I claim as new and desire to secure by Letters Patent, is:

The ornamental design for a carbureter body or casing as shown.

In testimony whereof I affix my signature in presence of two witnesses.

CHARLES E. JOHNSON.
